UNITED STATES PATENT OFFICE.

CROMWELL HAMFORD VARLEY, OF CHILWORTH HILL, NEAR GUILDFORD, ENGLAND.

PUMP, ENGINE, AND THE LIKE.

Application filed November 6, 1923. Serial No. 673,071.

To all whom it may concern:

Be it known that I, CROMWELL HAMFORD VARLEY, a subject of the King of Great Britain, residing at Chilworth Hill, near 5 Guildford, in the county of Surrey, England, have invented certain new and useful Improvements in or Relating to Pumps, Engines, and the like, of which the following is a specification.

10 This invention relates to pumps, engines and the like of the kind described in my prior United States Patent No. 1,378,065 and in which a fluid displaced or displacing element (hereinafter termed the displacer) 15 is provided which is movable relatively to an enclosing casing in such manner as to maintain a travelling zone of contact, or approximate contact, with the walls thereof, the said displacer either driving or being 20 driven so that all points of the displacer move in circles of similar diameter, said movement being hereinafter termed a "paracyclic" movement.

In pumps and engines of the aforesaid 25 type as described in my United States Patent No. 1,378,065 the displacer was provided with flanges which extended beyond and worked upon flanged portions provided on the side plates of the enclosing casing, while, 30 in addition to a driving shaft, separate guiding eccentrics or their equivalent were also provided.

According to one feature of the present 35 invention, the aforesaid flanges are dispensed with, and the displacer is enclosed by, and works upon, the body portion or carcase of the pump, engine or the like so that it does not extend beyond the same.

According to another feature of the present 40 invention the use of separate guiding eccentrics or their equivalent is dispensed with and the displacer is driven and also guided in its so-called paracyclic movement through driving plates, gearing, eccentrics, 45 cranks or the like, which are also preferably located mainly or entirely within the casing of the apparatus. To these ends the enclosing casing may be constituted by a hollow casting provided with a central web 50 which acts as a support for a pair of driving and guiding eccentrics, disc cranks or their equivalent, said web also constituting the rear working face of the displacer, the front working face being constituted by a 55 cover plate which is detachably connected to the casting. A centrally disposed boss is

also provided which may be formed integral with the casting, said boss serving as an inner working face for the displacer. The rear cover plate may also be provided 60 with recesses to accommodate the rear ends of the shafts of the eccentrics or cranks which drive and guide the displacer as also with a bearing for the shaft which drives, for example through spur gearing, the said 65 eccentrics or cranks.

According to a further feature of the present invention the displacer, or the external casing, as also a fixed inner member around which the displacer works, is or are provided with packing pieces which are so constructed and arranged as automatically to take up for wear.

The packing pieces may be positioned either in the displacer or in the body portion or casing or certain of the packing pieces may be located within the displacer and the remainder in the body portion.

In order that the said invention may be clearly understood and readily carried into 80 effect the same will now be described more fully with reference to the accompanying drawing which shows by way of example two constructional forms of pumps embodying the three aforesaid features in combination, and in which:—

Figure 1 is an elevation of one form of pump with the front cover plate removed as also a bolt which holds the front and rear cover plates to the body portion of the 90 pump.

Figure 2 is a section on the line 2—2 of Figure 1, the displacer being shown in approximately the position which it takes up when in its extreme lateral position.

Figure 3 is a view corresponding to Figure 1 showing a modified construction of pump.

Figure 4, 5 and 6 are detail views showing modified forms of packing pieces.

A is the displacer which, in the example shown at Figures 1 and 2 is constituted by a gapped cylinder. B is the enclosing casing which, in the example shown at Figures 1 and 2 is of cylindrical formation. B' is the 105 central web, C is the front cover plate and D is the rear cover plate. It will be observed that the web B', the sides of the casing B, and the front cover plate C, completely 110 enclose the displacer A, these parts thus forming outer working faces for the displacer A. An inner working face is provided by a cy-

lindrical boss E, which, in the example shown, is carried by a web e, the web e also serving as a partition which divides the suction from the delivery side of the pump. The front cover plate C is secured to the central web B' by a bolt F and nut F', the head F² of the bolt being formed with a recessed portion which acts as a support for the front end of the driving shaft G. H, H are the combined guiding and driving elements which, in the examples shown, are constituted by disc cranks, the crank pin h' of each crank extending into a recess in the displacer A, said recess being provided with a liner a. The disc h² of each crank rotates within a liner b in the web B' and the rear end of each crank shaft is supported within a recess in the rear cover plate D, said recess being also provided with a liner d. The driving shaft G rotates within a bearing g in the rear cover plate D. Keyed to the driving shaft G is a pinion I which engages with pinions J, J keyed to each of the disc cranks H, G. Each of the pinions J, J is provided with a counterweight J' so as to balance the parts. Owing to this arrangement, and on the shaft G being driven, the pinion I will drive the pinions J, J and consequently the disc cranks H, H so that a paracyclic movement will be imparted to the displacer A.

The displacer A, as also the central boss E, is provided with packing which, in the examples shown, is constituted by wedge-like pieces K of suitable material inserted in undercut slots k', k'. Positioned beneath each wedge-shaped piece K is a spring h² which tends to thrust the packing outwards, each spring, in the examples shown, being constituted by a piece of resilient steel wire of sinuous formation. Mounted within a recess l in the front face of the displacer A is a strip of packing material L, the recess l being closed at each end by the two filling pieces l'. A similar strip of packing material (not shown) is provided and located within a recess in the rear face of the displacer, this second packing strip being interrupted at the points where the pins h' of the crank K enter the displacer.

Instead of a pair of cranks, more than two can be employed; for example, four cranks may be used, one crank being placed between each pair of packing pieces K, K.

In the modified arrangement shown at Figure 3 the displacer is formed with bosses A', A', which accommodate the crank pins h', h', the latter being of massive construction, and the sides of the casing B are formed with recesses B², B², to adapt the same to the modified construction of displacer. The surfaces a^x, a^x of the casing B, the displacer A, and the central boss E, E, have identical curvatures, and, to this end, are struck from the same centre, while the

surfaces a^{xx}, a^{xx} of the bosses A', A', and of the interior surface of the recesses B², B² are also of similar curvature. In this embodiment of the invention the packing pieces K, K are adapted to co-operate with surfaces K', K', constituted by inserted and replaceable metal strips which are so shaped as to enable contact to be made during a portion of the cycle without the packing pieces being appreciably moved in a direction more or less at right angles to the direction of rub. To this end the surfaces K', K', are struck from centres having radii corresponding to the stroke of the cranks; for example, in cases where the cranks have a throw of 1", and accordingly a stroke of 2", the curved surfaces K', K', would have a radius of 2".

In addition to the driving pinions J, J, cranks may be provided at the ends of the shafts H, H and connected together by a tie member or connecting rod (not shown), said cranks being located outside the casing and at right angles to the cranks h', h² so as to ensure a smooth passage over the dead centre. The connecting rod located between the aforesaid additional cranks may, in certain cases, serve as the driving member for the shafts H, H; the pinions J, J and I and the shaft G being dispensed with.

In the modified constructions of packing shown at Figures 4, 5 and 6 each piece is formed in two parts m, m' situated within an undercut recess and pressed outwards by a sinuous piece of spring steel m². The packing piece shown in sectional end view at Figure 4 may be used in place of the packing L, the part m' thereof being wedge-shaped and positioned above one of the humps of the spring m² so that it is pressed upwards and outwards as the packing piece is worn down, thereby compensating automatically for wear. Figure 5 is a longitudinal section and Figure 6 is an end view of a packing piece which may replace the packing pieces K, K. In this instance the spring m² acts both to push the parts outwards as wear takes place and also to maintain them by endwise pressure in close contact with the cover C' and web B'. Holes or slots may be formed in the side faces of the packing strips so as to accelerate wear on these surfaces, and by thus reducing the thickness of the wedges, to allow them to protrude further out so as to take up the wear on the contacting portions.

Packing pieces may also be provided with ends having faces which meet at an angle. Balance weights may be used where necessary or in the case of cranks the arrangement of the tie rod may be so chosen as to effect the necessary balance. Eccentrics may also be used in place of cranks and vice versa, while suitable oiling arrangements may be added where desired.

In view of the fact that the displacer ele-

ment A or A' has a paracyclic movement imparted thereto, in contra-distinction to an eccentric movement, it is possible to employ resilient packing pieces having flat rubbing surfaces which engage on flat facets on the casing or on the displacer element A or A', which facets are parallel to the flat rubbing surfaces of the packing pieces, thus producing increased efficiency. The packing 10 pieces, as also the facets, are preferably made replaceable.

What I claim and desire to secure by Letters Patent of the United States is:—

1. An engine or pump of the kind set forth comprising a displacer, means for imparting a paracyclic movement to said displacer, a hollow casing surrounding said displacer and forming a working face for the exterior face thereof, a central web on 20 said casing which constitutes a working face for the rear side of said displacer, and a cover plate detachably connected to the casing which forms a working face for the front of said displacer.

2. An engine or pump of the kind set forth comprising a displacer, means for imparting a paracyclic movement to said displacer, a casing enclosing said displacer and forming a working face for the exterior face of 30 said displacer, a central web on said casing which constitutes a working face for the rear side of said displacer, a cover plate detachably connected to the casing which forms a working face for the front of said displacer, and a central boss which serves as a working face for the inner face of said displacer.

3. An engine or pump of the kind set forth comprising a displacer, means for imparting a paracyclic movement to said displacer, a casing enclosing said displacer and forming a working face for the exterior face of 40 said displacer, a central web on said casing which constitutes a working face for the rear side of said displacer, a cover plate which forms a working face for the front of said displacer, packing pieces between 45 said displacer and said casing, and means for automatically taking up for wear on said packing pieces.

4. An engine or pump of the kind set forth comprising a displacer, a casing enclosing said displacer and forming a working face for the exterior of said displacer, a central 55 web on said casing which constitutes a working face for the rear side of said displacer, a cover plate which forms a working face for the front side of the displacer, a central

boss which serves as a working face for the interior side of such displacer, packing 60 pieces between said displacer said boss and said casing and means for automatically taking up for wear on said packing pieces.

5. An engine or pump of the kind set forth comprising a displacer, a casing enclosing 65 said displacer, and combined driving and guiding means which both drive and also guide said displacer in such manner that all points of the displacer move in circles of similar diameter relatively to the casing, while maintaining a traveling zone of contact with the enclosing walls thereof.

6. An engine or pump of the kind set forth comprising a displacer, a casing enclosing 70 said displacer in such manner that the walls thereof form working faces both for the exterior face and also the sides of the displacer, a central web in said casing and combined driving and guiding means partly supported by said central web which serve 75 both to drive and also to guide said displacer so that it has a paracyclic movement imparted thereto.

7. An engine or pump of the kind set forth comprising a displacer element entirely enclosed by and adapted to be displaced within a chamber in such a manner as to maintain a traveling zone of contact with the walls thereof, a pair of crank members directly attached to said element said crank 90 members being adapted both to rotate and also to guide the displacer in such manner that all points thereof move in circles of similar diameter.

8. An engine or pump of the kind set forth comprising a displacer, a casing enclosing 95 said displacer, a rear cover plate, a central web, crank members disposed between said rear cover plate and said central web and adapted to impart a paracyclic movement to 100 said displacer, a driving shaft, spur gearing, said cranks being arranged on each side of said driving shaft and being driven through said spur gearing.

9. An engine or pump of the kind set forth 105 comprising a displacer, means for imparting a paracyclic movement to said displacer, a casing enclosing said displacer and forming a working face for the outer surface of said displacer, flat facets on said casing and packing pieces having flat rubbing surfaces 110 which engage said flat facets on the casing said flat faces being parallel to the flat rubbing surfaces of the packing pieces.

CROMWELL HAMFORD VARLEY.
